UNITED STATES PATENT OFFICE

ROBERT OSKAR KRASSELT, OF LEIPZIG, GERMANY

LOCKING DEVICE FOR CLOSET AND LAVATORY DOORS

Application filed April 2, 1929, Serial No. 352,040, and in Germany June 21, 1928.

The invention concerns that class of locking devices for closet and lavatory doors in which the door is moved by a spring into a semi-open position and held securely thereby 5 a locking device which engages in a socket, or hole, in a guide rail fixed to the door frame.

The advantage possessed by this class of locking device is that they permit of observation of the room when not in use but do not 10 allow it to be entered without summoning the attendant or the insertion of a coin.

Hitherto it has only been possible to utilize this class of locking device for closets or 15 lavatories which are permanently under the observation of an attendant whose intervention was available for releasing the locking device with the aid of a special key. The customary coin freed locking devices are not 20 capable of being used for this class of locking device because the inserted coin must remain available for the backward movement of the locking bolt until the door is completely closed as, after the coin is inserted, 25 the locking bolt must first be withdrawn from the locking socket and the door swung sufficiently open to enable the room to be entered and only then is the lock to be actuated in such a way that the door may be 30 completely closed. The inserted coin must remain in a position to release the mechanism during the entire cycle of this opening and subsequent shutting of the door.

These requirements have been taken into 35 consideration in the invention namely that the locking bolt is to be coupled to an auxiliary bolt which can be moved by hand the coin being retained in a definite location between both the bolts by gripping pieces 40 which are formed with steps on them in such a position that it connects the auxiliary to the locking bolt and cannot fall before the couple is broken by the action of completely closing the door which must itself be opened 45 sufficiently to enable the sliding locking bolt to pass over a rising path thus permitting the coin to come to rest between the separated parts of the gripping pieces and having thus lost its support to fall freely down.

50 Furthermore in accordance with the in-

vention precautions are taken that the locking socket provided for the spring actuated locking bolt cannot be improperly screened and the locking bolt thus prevented from engaging in the locking socket thus making it 55 possible to close the door without the insertion of a coin. Care is also taken to prevent opening from the outside, during use of the room, provided the door has been correctly 60 closed.

The drawings illustrate an example of the application of the invention.

They show:—

Fig. 1 the interior view of the door lock when the door is closed.

Fig. 2 a sectional plan view of the locking mechanism when the door is in the securely held partially open position in the condition shown in Fig. 1.

Fig. 3 a view showing part of the interior 70 of the lock.

Fig. 4 a cross section of the lock with the rod for moving the bolt.

Figs. 5-7 a cross section of the lock with 75 the coin in various positions.

Fig. 8 a sketch of the application in accordance with Fig. 4.

Fig. 9 a portion of the partially opened door with the locking bolt dropped into the holding socket, shown in section.

Fig. 10 the door whilst being opened.

Fig. 11 a sketch of a portion of the guiding rail with its holding socket.

Fig. 12 another sketch of Fig. 11.

Fig. 13 an interior view of the interlocking device for the closed door when the door is in the open position.

Fig. 14 a sectional plan view of Fig. 13.

Fig. 15 the position of the interlocking device when the door is in the closed position.

Fig. 16 a sectional plan view of Fig. 15.

Fig. 17 a view of the exterior of a door provided with the interlocking device.

The locking bolt "a" subjected to the pressure of the spring "b" is fixed inside a lock container (see Figs. 9 and 10) and slides over the rail "d" which is attached to the door frame and has in it at an appropriate distance from the door frame a locking socket 100

"g" (see Fig. 10) arranged in such a manner that if the bolt "a" has passed into the socket the door will remain open to such an amount that a narrow slit is left sufficient to permit a view into the room but which will not permit anybody to pass into it (see Fig. 9).

Inside the lock container the locking bolt "a" is provided with a block "h" in the side of which there is an open coin passage (see Figs. 1 and 3). The auxiliary bolt "k" is placed, inside the lock container parallel to the locking bolt "a" and arranged to be withdrawable against the pressure of the spring "b" by means of the cam shaft "m" (see Figs. 1 and 2). This cam shaft has a handle attached to both ends so that it can be actuated from either side of the door (see Fig. 10).

Inside the lock container below the bolts "a" "k" a plate "n" with a perforation "n'" is fixed which is held by the latching links "o" which move on the axes "v" (see Figs. 2-7) both the latching links are held by springs "f" pressed against stops, not shown in the drawing, so that they occupy the positions shown in Fig. 2 and Figs. 5 and 7. The latching links "o" are shaped with inwardly directed slants behind which they have stepped surfaces.

If the door is to be freed the coin is inserted in the customary aperture and passing through the coin way falls into the slot in the block "h" resting between the slanting front parts of the latching links "o" (see Fig. 2). If the cam shaft "m" is now turned in a suitable manner the auxiliary bolt "k" in the lock is drawn back and its hook "k", with the aid of the coin compels the locking bolt to combine in the movement thus causing it to be withdrawn from the holding socket "g" in the locking rail "d".

This movement grips the coin between the two bolts "a" and "k" and it is forced beyond the noses of the latching links "o" where it is held firmly behind the first steps of the latching links when the shaft "m" is released (see Fig. 5).

When the door is quite shut the locking bolt rises on a track (see Figs. 9-10) on the inside of the locking track during which the coin is able to remain behind the second step of the latching link (see Fig. 6) and then to be released and free to drop down.

When the door is opened after the room has been used the locking lever "a" pushes in the well known manner cover "p" of the locking socket "g" in front of it (see Figs. 6 and 10) so as to enable it to pass over the covered socket "g". The subsequent closing movement of the door is followed by a dropping of the bolt "a" into the locking socket "g" which retains the door in the partially open position (see Figs. 7 and 9).

To prevent any interference resulting from the insertion of false coins the coin inlet is provided with a coin tester that is

put into operation by every closing motion of the door and also swung forwards by every utilization of the cam shaft "m".

The coin inlet passage "g" of the coin tester comprises the fixed inclined wall "r" and the wall "r'" which can be moved on the hinge "s" (see Figs. 1 and 3) and which is pressed by springs (not shown) against the wall "r". The coin which is inserted, if a thin false coin falls through the narrow slot (not shown) from the passage "g" into the ejector run-way "v" and is thus ejected.

False coins of the correct thickness but of incorrect diameter will run through the coin passage but will be held by other well known means from actuating the releasing mechanism. Other coins which due to their peculiarity become wedged in the coin passage and consequently interfere with the operation can be got rid of as the lower part of the inclined passage wall of the coin tester "r" can be opened by pressure against the spring pressed wall "r'". This is moved by the bolt "k" actuated by the releasing part (4) which is held so as to be able to move freely around the pin (3) on the rectangular piece (2) to the extent allowed by the slot (5) therein receiving a guide and limitation pin (6) attached to the bolt "k" (see Figs. 2 and 3). It is advisable to provide the apparatus with the coin inlets or coin testers on both sides, as the releasing part (4) is so contrived that for each outward swing both passages of the coin tester are opened. When the door is fully closed the locking bolt "a" is pushed back into the lock by the rising part of the guiding rail "d" (Figs. 9 and 10) thus enabling the block "h" to force upwards the pin "z" against the wall "r" (see Figs. 1 and 3). By this means the inserted coins are immediately ejected and unable to reach the freeing mechanism at inopportune times i. e. when the room has been used.

In order to prevent the push piece (p) of the covered locking slot of the guiding rail (d) being covered by assisting means not belonging to the device during the closing movement which follows the opening of the door the guiding rail (d) is made with a closed entry into the inner part of which the locking bolt passes when the door is closed moving a flap which during the further closing movement closes the front entry of the guiding rail.

Until this time the entry to the guiding rail remains closed for the purpose of securing the locking bolt against the insertion of improper objects which would prevent the locking bolt "a" entering the guiding rail (d) and which might also under these circumstances prevent the closing of the door or the further movement of the counting mechanism, not shown in the drawings, which only operates when the door is completely closed.

Inside the enclosed screened guiding rail (d) there is attached at a suitable distance from and opposite to its upper surface a running track (d) in which is the holding socket 5 for the locking bolt (a), which is, with advantage, provided with a roller (a). The push plate (p) is forced during the opening of the door by the pressure of the locking bolt (a) over the entry to the locking socket. The front end of the locking bolt passes along a slot, of dimension appropriate to the size of locking bolt (see Figs. 11 and 12) fixed at that part of the guiding rail and having a channel formed bent or angular flap (x) 10 movable about the pin (y) which generally remains in such a position that its front opening is in the vicinity of the projecting opening of the guiding rail (d) (see Figs. 11 and 12).

When closing the previously opened door (see Fig. 1) the locking bolt (a) will project into the housing (d) and the channel form flap X will be swung around on its pin y in such a manner that finally the front opening 20 of the housing (d) will be screened or in other words the closing of the door is, until the locking bolt (a) enters the socket (g), only possible when no foreign bodies are inside the housing (d). As in addition to this 25 the front edge of the door when it is being closed will sweep along the upper surface of guiding rail, it is also impossible to force back the bolt (a), by any supplementary aids, against the pressure of its actuating spring, as it is obvious that the movement of the locking bolt (a) is so limited in this direction that it can only enter the front portion of the housing (d). The arrangement shown in 30 Figs. 4 and 8 is provided to enable the attendant to open the door, without using a coin, by means of a socketed key. The socketed key is pushed over the squared spindle 7 which is firmly attached to the lever 9. The connecting links 10 and 11 are attached to the bell crank lever 11 which moves around a pin 45 13 fixed to the projecting part of the container and to lever 9 and to the block (h). When the squared spindle is turned by means of the socketed key the lever 9 moves around the axis 8 towards one side and moves the block h through the intervention of the parts 10, 50 11 and 14. As the locking bolt only retains the door in a semi-open position the retention of the door in a completely closed position 55 must be effected by an interlocking device that can only be opened from the inner side.

The interlocking device can with advantage be combined with the indicator signal which shows whether the room is occupied 60 or free (see Figs. 13 to 17) and comprises a locking receptacle 16 fixed to the door frame having a bolt 15 which is permanently pressed outwards by the spring 17, and a lock 19 attached to the door in such a manner that the auxiliary bolt 18 is opposite to the bolt 15.

The auxiliary bolt 18 is geared through the toothed gear wheel to the actual locking bolt 18. The spindle 24 belonging to the toothed wheel is, together with the pressure handle 23, fixed on the inner side of the door while the indicating plate 22 (Fig. 17) is on the outer side together with a flat sided attachment which permits the attendant, in case of emergency, to actuate the interlocking mechanism from the outer side of the door. 70

It will be seen from Figs. 15 and 16 that when the door is shut bolt 15 forces the auxiliary bolt 18 backwards into the lock 19 thus causing the toothed wheel 20 to rotate a suitable amount with the result that the indicating disc moves from "free" to "occupied" 80 while the locking bolt 21 is simultaneously forced into the locking receptacle and the door is consequently securely bolted. 75

What I claim as my invention and desire to secure by Letters Patent of the United States is:—

1. A coin controlled locking mechanism for doors for locking the door in a partly open position and upon the insertion of a coin 90 permitting of the door being unlocked and opened and the locking mechanism retained by the inserted coin in position to permit of the door being fully closed and locked when closed, said mechanism comprising normally disconnected automatically projectible main and auxiliary locking bolts on the door, a locking device on the door frame having a keeper, engageable respectively by said bolts, for locking the door in partly open and closed 100 positions, and a part for holding the main bolt retracted when the door is closed, coin holding and releasing means for coupling the main bolt with the auxiliary bolt, and means for shifting the auxiliary locking bolt to retract the main locking bolt on a coupling connection being effected by a coin. 105

2. A coin controlled door locking mechanism of the character set forth in claim 1 110 wherein the means for shifting the auxiliary locking bolt comprises a manually operable element actuatable to retract the main locking bolt through the auxiliary locking bolt and then to release the latter for a locking action. 115

3. A coin controlled door locking mechanism of the character set forth in claim 1 120 wherein the locking device on the door frame comprises a channeled keeper having a keeper opening and a surface for action on the main locking bolt to hold the bolt retracted.

4. A coin controlled door locking mechanism of the character set forth in claim 1 125 wherein the locking device on the door frame comprises a channeled keeper having a keeper opening and a guide rail having an inclined surface for action on the main locking bolt to hold the bolt retracted.

5. A coin controlled door locking mechanism of the character set forth in claim 1 130 wherein the locking device on the door frame

comprises a channeled keeper having a keeper opening, a surface for action on the main locking bolt to hold said bolt retracted, and a cover for the opening shiftable by the bolt to cover and uncover said opening.

5 6. A coin controlled door locking mechanism of the character set forth in claim 1 wherein the locking device on the door frame comprises a channeled keeper having an entranceway, a keeper opening to receive the bolts, a surface for action on the main locking bolt to hold said bolt retracted, and a pivoted guard for closing said entranceway and adapted to open under pressure of the 10 entering main bolt.

15 7. A locking device in accordance with claim 1 having a coin insertion passage terminating in a block fixed to the main locking bolt and having a coin slot opening in 20 the direction of the auxiliary bolt, and means engageable by the coin in said opening to couple the bolts so that when the auxiliary bolt is thrown back the main locking bolt is caused by pressure of the coin against it to be 25 retracted.

30 8. A locking device in accordance with claim 1 including a slotted coin receiving member fixed to the main locking bolt and pivoted dogs carried by the bolts and each having an inclined nose and abutment shoulders at different distances from the nose for engagement of the coin therewith, whereby the inserted coin is connected to and couples the bolts for conjoint movement.

35 9. A locking device in accordance with claim 1 in which the coin holding and releasing means includes a slotted coin receiving member carried by the main locking bolt, and means carried by the bolts for engagement with the coin, whereby the bolts are coupled, and a coin conductor leading to the slotted coin receiving device and having arranged therein a retarder governing the passage of the coin.

40 45 10. A locking device in accordance with claim 1 wherein means are provided for retracting the auxiliary locking bolt from either side of the door.

In witness whereof I have signed this specification.

ROBERT OSKAR KRASSELT.
